UNITED STATES PATENT OFFICE.

CARL WALKER KENDALL, OF GLENSIDE, PENNSYLVANIA, ASSIGNOR TO COLUMBIA MACHINE AND STOPPER CO. INC., OF NEW YORK, N. Y.; A CORPORATION OF NEW YORK.

BOTTLE-CAPPING MACHINE.

Application filed June 4, 1920. Serial No. 386,613.

To all whom it may concern:

Be it known that I, CARL WALKER KENDALL, a citizen of the United States, residing at Glenside, in the county of Montgomery and State of Pennsylvania, have invented certain new and useful Improvements in Bottle-Capping Machines, of which the following is a specification.

This invention is a bottle capping machine of the kind used in applying a bottle closure generally known as the crown seal. The machine of the present invention is an improvement upon that covered by United States Letters Patent No. 1,299,355, of April 1, 1919, for bottle capping machine. The principal objects of the invention are; first, to obtain a machine which with very little trouble may be reversed as to its direction of operation so as thereby to convert it into either a righthand or a lefthand machine according to the requirements of any particular installation; and second, to obviate the dragging of the bottles over the bottle support while still preserving a straight line horizontal movement of the bottles as in the above noted patented machine. Other more particular objects and advantages of the machine of the present invention will herein-after appear.

The construction and operation of the double capping head, including its orbital movement in a vertical plane, are substantially the same in the machine of the present invention as in the above noted patented machine, but radical changes and improvements have been made in the bottle carriage mechanism by which the bottles are supported and moved horizontally in a given vertical plane beneath the capping head. The present invention more particularly includes features of construction and combinations of parts as will appear from the following description.

I shall now describe the bottle capping machine embodying the present invention illustrated in the accompanying drawings and shall thereafter point out the invention in claims.

Figure 1 is a central vertical section from front to back of the complete machine with parts omitted, the section being taken on planes indicated by the line 1—1 of Figures

2, 3 and 4, as viewed from the right, and in the upright position of the machine appearing in Figures 2 and 4.

Figure 2 is a front elevation of the machine as viewed from the left in Figure 1 and partly in section on vertical planes indicated by the line 2—2 of Figures 1 and 3.

Figure 3 is a plan view with parts in horizontal section on planes indicated by the line 3—3 of Figures 1 and 2.

Figure 4 is an enlarged vertical section of the bottle carriage mechanism on planes indicated by the line 4—4 of Figures 1 and 3.

Figure 5 is a further enlarged perspective view of one of the bottle-supporting links or plate members of the endless chain bottle carrier.

Figure 6 is an inverted plan view of two such connected links.

A main frame casting 1 carries a bracket upon which is mounted a motor 2 which drives a vertical main shaft 3 through spur gearing 4 and worm gearing housed in the gear box 5. Through three pairs of beveled gears 6, 7 and 8, the vertical main shaft 3 drives three horizontal shafts 9, 10 and 11 all at the same rotative speed and arranged in a common vertical plane. The upper and the middle shafts 9 and 10 drive the orbitally moving capping head while the lower shaft 11 drives the intermittently moving endless chain bottle carrier and its adjuncts embodying features of my present invention in combination with the orbitally moving capping head, the orbital movement of which is substantially the same as in the above noted patented construction.

The construction and operation of the double capping head, illustrated in the accompanying drawings, are familiar and the means for imparting orbital movement thereto are substantially the same as disclosed in the above noted patent and therefore need be described only briefly for present purposes.

On the front ends of the shafts 9 and 10 are eccentrics 12 and 13 which carry a vertical orbit link 14 upon which the capping head is mounted for vertical adjustment by means of lugs 15 on the capping head barrels 16, one of which appears in Figure 1, and the two of which are connected integral-

ly by means of a web 17. It is necessary to adjust the vertical position of the capping head to various elevations above the bottle carrier or bottle carriage in order to adapt the machine to bottles of various heights and this adjustment is effected by means of a vertical screw 18, whose thread turns in a lug 19 on the orbit link 14 and whose upper end is journaled in a lug 20 on the capping head connecting web 17. The screw 18 may be turned by means of a pair of bevel gears 21 and a key shaft 22 journaled in the capping head web 17 and projecting forward through the main member 23 of the cap conveyer.

15 The driving shaft 11 for the endless chain bottle carrier or bottle carriage is journaled in a supporting bracket 24 secured on the main frame part 1 and at its forward end this shaft carries an inner driving arm 25 which carries a pair of diametrically oppositely disposed eccentric pins 26, the outer ends of which are supported by an outer arm 27 which is fixed upon a stub shaft 28 journaled in an outboard bearing 29 secured to the supporting bracket 24. Rollers 30 are mounted upon the eccentric pins 26, the eccentricity of these pins being equal and also this eccentricity being equal to the eccentricity or throw of the eccentrics 12 and 13, these eccentrics and the eccentric pins 26 being arranged in phase correspondence as shown in Figure 1. The two rollers 30 are adapted alternately to engage in downwardly opening open slots formed between depending projections 31 formed on the lower side of bottle-supporting links 32 which are pivotally connected together by means of pivot pins 33 to form an endless chain bottle carrier or bottle carriage. The bottle-supporting links 32 of the bottle carrier ride upon small rollers 34 journaled upon the pivot pins 33 and which roll upon tracks 35 secured to the carriage-supporting brackets 24, and these bottle supporting links 32 are held in place by guide bars 36 and set flush in grooves in the upper marginal surface of the links 32 and of the supporting bracket 24 and are secured to the bracket 24. The endless bottle carrying chain made up of the connected bottle supporting links 32 is supported by similar sprocket wheels 37 and 38 having therein peripheral substantially semi-circular notches which are adapted to receive the small rollers 34 on the links connecting the pivot pins 33, as shown in Figure 2. The sprocket wheel 37 is supported by a shaft 39, and the sprocket wheel 38 is fixed upon a shaft 40, these shafts 39 and 40 being supported by brackets projecting from the supporting bracket 24 as shown in Figure 2.

65 The radius of each of the turret-driving pins 26 is the same as the radii of the equal throw eccentrics 12 and 13, which carry the orbitally revolving capping head, and these eccentrics and the pins 26 are set in synchronism so that the intermittent forward movement imparted by the eccentric pins 26 to the successive links 32, each of which is adapted to carry a bottle, will at all times correspond exactly with the horizontal component of movement of the capping head, whereby the relative movement between the bottle carriage links 32 and the capping head is reduced to the simple vertical component of the capping head movement. In other words, there is no relative horizontal movement between the bottle-carrying links 32 of the bottle carriage and the capping head. A resilient pad 41 is set flush in the upper surface of each of the bottle-supporting links 32 concentrically with the capping head to receive the bottles while under the pressure of the capping operation.

10 The forward end of the sprocket shaft 40 is geared by means of bevel gears 42 and 43 to a short horizontal shaft 44 which in turn at its other end is geared by means of bevel gears 45 and 46 to the lower end of a vertical bottle-feeding star wheel shaft 47 journaled in a supporting bracket 48 secured to the main supporting bracket 24. At its upper end the star wheel shaft 47 drives a bottle-feeding star wheel 49. The bottle-feeding star wheel 49 rotates above the surface of a small feed table 50 provided with an outer curved curb 51 for guiding the bottles, a spring pressed curved bottle guide 52 forming a continuation of this curb and being pressed towards the star wheel and against the bottles by a coiled thrust spring 53 surrounding a headed stud 54 carried by the rail or curb 51. The curb 51 and the spring-pressed bottle guard 52 co-operate with the star wheel 49 to deliver the bottles successively in correct position centered upon the resilient pads 41 of the bottle-supporting links 32 of the endless chain bottle carrier or bottle carriage.

15 The driving means for the bottle-feeding star wheel 49 are adapted to permit this star wheel to yield rotatively to prevent the breaking of bottles should for any reason the bottles become jammed on the feed table 50 between the star wheel 49 and the curb 51. On the top of the star wheel 49 there is secured a driving disc 55, for example by means of a pin 56, as shown in Figures 2 and 3. A flanged cap 57 is secured upon the upper end of the star wheel shaft 47 by means of a pair of set screws 58 (Figure 3) adapted to enter an annular groove 59 (Figure 2) in the upper end of the star wheel shaft 47 so that this driving cap 57 may be fixed to the star wheel shaft 47 to rotate therewith. The driving cap 57 is shown as further held in place by means of a washer 60 and tap bolt 61 screwed into the upper end of the star wheel shaft 47. The driving disc 55 on the star wheel 49 is provided on

its upper side with one or more, shown as two (Figure 2), hollowed out recesses 62 adapted to receive the lower rounded end of a spring-pressed driving plunger 63 carried by the driving cap 57 and pressed downward by a coiled thrust spring 64. Should the bottles become jammed, then the lower rounded end of the spring-pressed driving plunger 63 will slip out of whichever of the recesses 62 it happens to be engaged in, permitting the star wheel shaft 47 to rotate independently while the bottle-feeding star wheel 49 may remain stationary until the jammed bottles are released. The driving 15 gearing for the bottle-feeding star wheel 49 is of course so proportioned as to drive the star wheel in proper timed relation with the movements of the endless chain bottle carrier formed by the pivotally connected 20 bottle-supporting links 32 and in view of the fact that the star wheel 49 is driven from the sprocket wheel 38 of this endless chain bottle carrier, it is evident that the star wheel will partake of the same intermittent 25 movements that are imparted to the bottle-supporting links 32 and hereinbefore described.

A bottle conveyer is provided for bringing the bottles up to the star wheel 49 and feed table 50. This bottle conveyer comprises a plurality, shown as three, of parallel conveyer chains 65 adapted to travel in their upper stretches in grooves formed by a floor 66 between longitudinal ribs 67. This 30 bottle conveyer is shown as arranged at an inclination to the front of the machine and as having a supporting frame 68 secured to the star wheel bracket 48. At the outer end of the supporting frame 68, the conveyer chains 65 are supported by a sprocket-carrying outer shaft 69 journaled in the outer end of the frame 68 and these chains are similarly supported at the inner end of the frame 68 by a similar sprocket-carrying 35 shaft 70 which forms a driving shaft for the conveyer chains 65. The conveyer chains 65 are driven in bottle-progressing direction by means of driving connections from the outer end of the stub shaft 28, which, as hereinbefore described, forms virtually a continuation of the bottle carrier shaft 11. These driving connections comprise a spur gear 71 on the outer end of the stub shaft 28, a similar spur gear 72 on the inner end 40 of a short hollow shaft 73 journaled in an outer bracket 74 and connected at its outer end by a pair of bevel gears 75 with the adjacent end of a short horizontal shaft 76 also journaled in the outer bracket 74 as shown in Figure 3. The adjacent projecting ends of the short horizontal shaft 76 and of the conveyer driving shaft 70 are connected together by means of a flexible 45 driving shaft 77, shown as including a pair of universal joints.

Each time the capping head descends in its orbital movement two bottles are capped. The bottles are advanced the distance of one bottle from another, corresponding to the successive bottle-carrying links 32, during 70 the upper and reverse part of the orbital movement of the capping head, as illustrated in the drawings, of which particularly see Figure 1, this advance being accomplished by one of the eccentric pins 26, namely, that 75 which is uppermost as shown in Figure 1. During the next half rotation of the bottle carriage shaft 11, the lower eccentric pin 26, appearing in Figure 1, comes into play during the downward and lateral orbital 80 movement of the capping head, and advances the bottles through a further distance of one of the links 32. This brings two uncapped bottles directly under the capping head cylinders or barrels 16, so that the 85 two caps are applied during this advancing movement of the two bottles, and while, as above noted, the capping head and the bottles carried by the bottle-supporting links 90 32 are traveling forward in the same vertical plane at the same speed, this result being due, as above noted, to the equal eccentricity of the eccentric pins 26 and the eccentricities 95 12 and 13. Midway during both the upward and downward movement of the capping head in its orbit, the bottle-supporting links 32 of the intermittently moving carrier chain come to rest momentarily during the time that one of the roller-carrying eccentric pins 26 is passing out of the slot between the 100 link projections 31 of the bottle-supporting links 32, and while the other roller-carrying eccentric pin 26 is making its entrance into the next succeeding slot between these adjacent projections 31, as is clearly indicated 105 by broken lines in Figure 4, of the drawings.

This arrangement provides for the forward rectilinear movement of the bottles during the capping operation at the same speed as the horizontal component of movement of the orbital capping head without any dragging of the bottles over their supporting surfaces, the progression of the bottles being continually forward, together with their supports. The intermittent movement 110 of the endless bottle carriage, made up of the connected bottle-supporting links 32, and the corresponding intermittent movement of the bottle-feeding star wheel 49, provide time for the vertical component of the 115 orbitally moving capping head to take place and to permit the bottles to be fed forward at the same speed of transverse movement as the capping head during the capping operations. The capped bottles are delivered 120 onto a receiving shelf 78 projecting from the front of the machine at the left thereof in the machine illustrated in the drawings.

The machine illustrated in the drawings 130

moves the bottles transversely from right to left, as viewed from the front of the machine, and as shown in Figures 2, 3 and 4 of the drawings. By reason, however, of the above described construction of the bottle-feeding and bottle carriage mechanism, this machine may readily be transformed into a machine in which the direction of bottle-progressing movement is reversed so that the bottles would travel from left to right as viewed in Figures 2, 3 and 4 of the drawings in such a modified machine. In order to effect this transformation from a right hand to a left hand machine it is only necessary to move the conveyer frame 68 with its adjuncts from the right to the left side of the machine, it being necessary however to provide a left hand instead of a right hand supporting bracket, such as 48, for this conveyer and for the star wheel shaft 47, and also correspondingly to provide a left hand instead of a right hand star wheel. The driving connections including the flexible shaft 77 for the bottle conveyer are simply reversed from end to end, the supporting bracket 74 simply being turned half way around from the position thereof shown in Figure 3. Similarly, places are exchanged between the idler sprocket shaft 39 and the driving sprocket shaft 40 for operating the star wheel 49, as will be readily understood. The motor 2 is then simply arranged to drive the whole machine in the opposite direction.

35 It is obvious that various modifications may be made in the construction shown in the drawings and above particularly described within the principle and scope of my invention.

40 I claim:

1. A bottle capping machine comprising two vertical-plane eccentrics of equal throw, means for rotating them synchronously in angular phase correspondence, a capping head mounted on said eccentrics to be orbitally revolved thereby in a vertical plane, an endless chain bottle carrier below the capping head provided with a succession of open slots, a third eccentric adapted to engage in and to be disengaged from different ones of said slots and having a throw equal to the throw of said vertical plane eccentrics, and means for driving said third eccentric in synchronism and phase correspondence with said vertical plane eccentrics.

2. A bottle capping machine comprising two vertical-plane eccentrics of equal throw, means for rotating them synchronously in angular phase correspondence, a capping head mounted on said eccentrics to be orbitally revolved thereby in a vertical plane, an endless chain bottle carrier below the capping head having projections forming a series of open slots, a pair of dimetrical-

ly oppositely disposed eccentric pins adapted to work alternately in the successive slots and each having a throw equal to the throw of said vertical-plane eccentrics, and means for driving said pair of eccentric pins in synchronism and phase correspondence with said vertical plane eccentrics. 70

3. A bottle capping machine comprising three vertical-plane eccentrics of the same radii and two of which are located at a greater elevation than the third, means for rotating all three eccentrics synchronously in angular phase correspondence, a capping head mounted on the upper two of said eccentrics to be orbitally revolved thereby in a vertical plane, and an endless chain bottle carrier below the capping head and provided with a series of projections forming vertical slots adapted to be engaged by the lowermost of said eccentrics. 75 80 85

4. A bottle capping machine comprising a series of bottle-supporting and bottle-carrying members pivoted together to form an endless chain bottle carrier adapted to receive and thereafter intermittently move bottles transversely horizontally, means for movably supporting said endless chain bottle carrier, driving means adapted to impart to said endless chain bottle carrier intermittent bottle progressing movement, sprockets over which said chain passes, said sprockets being intermittently rotated by said chain, a bottle-feeding star wheel adapted and arranged to push the bottles into position upon the bottle-carrying supporting members of said endless chain bottle carrier, driving means for said star wheel connected to one of said sprockets for thereby intermittently rotating the star wheel along with the intermittent movement of said bottle carrier, a capping head, and means for imparting to said capping head a vertical component of movement to and from the bottles progressively as they are moved intermittently by said carrier. 90 95 100 105 110

5. The invention claimed in claim 4 in combination with an endless chain bottle conveyer for delivering the bottles to the star wheel, and driving means for said conveyer connected to the driving means for said endless chain bottle carrier. 115

6. A bottle capping machine comprising a series of bottle-supporting and bottle-carrying members pivoted together to form an endless chain bottle carrier adapted to receive and thereafter intermittently move bottles transversely horizontally, means for movably supporting said endless chain bottle carrier, driving means adapted to impart to said endless chain bottle carrier intermittent bottle progressing movement, sprockets over which said chain passes, said sprockets being intermittently rotated by said chain, a bottle-feeding star wheel adapted and arranged to push the bottles 120 125 130

into position upon the bottle-carrying supporting members of said endless chain bottle carrier, driving means for said star wheel connected to one of said sprockets for 5 thereby intermittently rotating the star wheel along with the intermittent movement of said bottle carrier, a capping head, means for imparting to said capping head a vertical component of movement to and from the bottles progressively as they are moved intermittently by said carrier, an endless chain bottle conveyor for delivering the bottles to the star wheel, driving means for 10 said conveyor connected to the driving means for said endless chain bottle carrier, and a spring-pressed bottle guiding member adapted to cooperate with said bottle conveyor and said star wheel in feeding 15

the bottles to the successive bottle-supporting members of the endless chain bottle carrier. 20

7. A bottle capping machine comprising a capping head, means for moving the capping head in a vertical plane in its cap applying operation, an endless chain bottle carrier below the capping head having projections forming a series of open slots, 25 a pair of diametrically oppositely disposed eccentric pins adapted to work alternately in the successive slots, and means for driving 30 said pair of eccentric pins in timed relation with the movement of the capping head in its cap-applying operations.

In testimony whereof, I have affixed my signature to this specification.

CARL WALKER KENDALL.
